(Cl. D61—1)

To all whom it may concern:

Be it known that we, Joseph Palma, Jr., and Courtney A. Leubner, citizens of the United States, and residents respectively of Berwyn, Cook County, State of Illinois, and Milwaukee, Milwaukee County, State of Wisconsin, have invented a new, original, and ornamental Design for Exposure Meter, of which the following is a specification, reference being had to the accompanying drawing, forming a part thereof.

Fig. 1 is a front elevational view of an exposure meter, showing our design;

Fig. 2 is a rear elevational view thereof;

Fig. 3 is a side elevational view thereof;

Fig. 4 is a top plan view thereof; and

Fig. 5 is a bottom plan view thereof.

The dominant feature of our design resides in the portions shown in full lines.

We claim:

The ornamental design for an exposure meter as shown and described.
